UNITED STATES PATENT OFFICE.

HARRY E. BREWIN AND ALEXANDER C. MACKEY, OF PLEASANTVILLE, NEW JERSEY.

DYEING MACHINE.

Application filed October 2, 1925. Serial No. 60,095.

Our invention relates to certain improvements in the dyeing machine for which application was filed by us on the 9th day of July, 1925, Serial No. 42,520.

5 The object of the present invention is to improve the means of driving the paddles, so as to more thoroughly circulate the dye liquor, and to provide means for supplying the vats with dye liquor independently of 10 the means for supplying water thereto.

In the accompanying drawings:

Fig. 1 is a plan view of our improved 15 dyeing machine;

Fig. 2 is a longitudinal sectional view 20 on the line 2—2, Fig. 4;

Fig. 3 is an end view; and

Fig. 4 is a transverse sectional view on 25 the line 4—4, Fig. 1.

The vat 1 is elongated and has a curved 30 bottom 2. Partitions 3 divide the vat into a series of compartments. The partitions are perforated to allow the dye liquor to circulate through all of the compartments, but the material to be dyed is confined in its 35 particular compartment.

In the bottom of the vat are perforated 40 sections 4, under which are perforated steam pipes 5. In the present instance two pipes are shown, one extending from one end of 45 the vat, and the other extending from the opposite end thereof. The steam heats the dye liquor in the vat.

The coloring matter is introduced into 50 the vat by means of small pipes 6, which extend diagonally from each of the vats to a partition. At this point each pipe has 55 two branches 7, one discharging into one compartment, and the other discharging into an adjoining compartment, as shown in Fig. 2. By this construction the coloring 60 matter is introduced into the vat in small quantities at different points. At the outer end of each pipe is a valve 8, and above the valve is a funnel 9.

On each end of the vat is a bearing 10, and on the central partition is a bearing 11. A longitudinal shaft 12 is mounted in the bearings. The shaft in this instance 65 does not rotate.

On the shaft 12 are four paddle-wheels 70 50, one for each compartment of the vat. Each wheel has solid side members 14 and paddles 15 attached thereto in any suitable manner. The particular construction of the 55 paddles may be modified without departing from the main features of the invention.

Mounted on a bracket 16 at one end of the vat is a reversing electric motor 17, which drives a longitudinal shaft 18 at the side of the vat through gearing 19, shown by dotted lines in Fig. 3. The gearing is located in 60 an enclosing casing 20.

The shaft 18 has its bearing in brackets 21 secured to the vat, as shown in Fig. 1. On the shaft are bevel gears 22, which mesh 65 with bevel gears 23 on transverse shafts 24 mounted in a bearing 25 on certain partitions of the vat. Each shaft 24 drives two paddle-wheels through a bevel gear 26 on the shaft, and bevel gear wheels 27 on the 70 paddle-wheels, so that the paddle-wheels rotate upon the fixed shaft 12.

By the above construction, one paddle-wheel of each pair rotates in one direction, 75 while the other paddle-wheel rotates in the opposite direction, and when the motor reverses, the direction of movement of all paddle-wheels is reversed. This causes the dye liquor in each compartment of the vat to circulate in a direction opposite to that in an adjoining compartment and through 80 the perforated partitions, insuring even dyeing.

The machine is especially adapted for 85 dyeing stockings, and other knit or woven fabrics, and wool and fur felts.

In ordinary practice, when stockings are 90 to be dyed, they are placed in bags or are otherwise arranged in batches, and each compartment contains a certain number of bags or batches.

We claim:

1. The combination in a dyeing machine, 95 of a vat; a series of transverse partitions in the vat forming compartments; a series of paddle-wheels, one paddle wheel for each compartment, said paddle-wheels being arranged in pairs; and means for driving the wheels of each pair in opposite directions.

2. The combination in a dyeing machine, 100 of a vat; a perforated transverse partition in the vat forming compartments; a paddle-wheel in each compartment; a bevel gear wheel on each paddle-wheel; a transverse shaft having a bevel gear wheel meshing 105 with the gear-wheels on the paddle-wheels; and means for driving the transverse shaft to cause the paddle-wheels to rotate in opposite directions.

3. The combination in a dyeing machine, 110 of a vat; a series of perforated transverse partitions in the vat; a longitudinal shaft

mounted on the vat; two pairs of paddle-wheels mounted on the shaft, the paddle-wheels being located in the compartments of the vat; a longitudinal shaft at the side 5 of the vat; means for driving the shaft; and transverse shafts geared to the longitudinal shaft and to each pair of paddle-wheels.

4. The combination in a dyeing machine, 10 of a vat having a series of perforated transverse partitions therein; steam pipes in the bottom of the vat; a small pipe for admitting coloring matter to the vat, said pipes

having branches opening into the compartments; a longitudinal shaft on the vat; a 15 paddle-wheel in each compartment and mounted on the shaft; a longitudinal driving shaft at the side of the vat; bevel gears thereon; transverse shafts having bevel gears at one end meshing with the gears on the driving shaft and having bevel gears at their opposite ends; and a bevel gear on each paddle-wheel meshing with the gears on the transverse shaft. 20

HARRY E. BREWIN.
